ELECTRICAL SIGNALING SYSTEM

Reginald Taylor and George Thomas Baker, Liverpool, England, assignors, by mesne assignments, to Automatic Electric Laboratories, Inc., Chicago, Ill., a corporation of Delaware

Application June 13, 1942, Serial No. 446,900
In Great Britain August 9, 1941

26 Claims. (Cl. 179—16)

The present invention relates to electrical signaling systems such as automatic telephone systems in which impulses are utilised to effect the positioning of selective apparatus and like operations, and it is more particularly concerned with arrangements for responding to control impulses whereby greater reliability may be obtained when signaling over lines of poor characteristics.

When impulses are transmitted over long non-repeated lines as are sometimes encountered in telephone systems, the received signals tend to be both highly attenuated and distorted so that impulses which when generated have make and break ratios within predetermined limits due to distortion cannot when received ensure reliable operation of the selectors in the distant exchange. Distortion may be due to the capacity effect of a long line, to low insulation resistance, to impedances connected across the line or to combinations of these, the general effect being to cause the impulses to depart considerably from a rectangular form. A further distortion is introduced due to the sluggishness of response of receiving equipment.

One of the objects of the present invention is to provide impulse-responding equipment which will reliably operate in response to such attenuated or distorted impulses even if the impulses themselves are insufficient to effect the impulses of the usual type of line relay.

In known impulsing arrangements the ratio of the make period of an impulse to the break period of an impulse is very important and when one allows for the variation in speed of subscribers' dial switches which is considered permissible, it will be clear that there is a serious restriction on the length of lines which can be used for direct dialling if the ratio of make to break periods of the contacts of the impulse responding relay are to be maintained within the prescribed limits for successful operation of the selectors.

An arrangement has been proposed in our application Serial No. 434,762 filed March 14, 1942, whereby the operation of selector switches need no longer be dependent upon the usual make to break ratios but rather upon the period which elapses between the corresponding parts of successive pulses so that the only limit is the actual speed of impulsing which must not be so slow that the period between similar parts of successive pulses exceeds a predetermined amount. When such period is exceeded, a switching operation is arranged to take place characteristic of the end of a series or of a release of a connection according to the final condition of the control circuit.

Such a method of impulsing is sometimes referred to as "speed timing."

It is a further object of the invention to guard against false operation by parasitic currents. Such parasitic currents which it is desirable to guard against are either low voltage currents which may persist or higher voltage currents which have a very short duration or are of a high frequency character.

10 The invention is characterized in that the receiving equipment for responding to the signals or impulses is not operative in accordance with the actual value of the signaling or impulsing currents but in accordance with the change or changes which take place when a signal or impulse is transmitted, e. g. when one condition of current flow changes or when one condition of current flow changes and restores. When the invention is applied to alternating currents which may be of the power frequency or voice frequency type or even of the carrier type it is necessary to provide means to respond to the actual rise and fall of the envelope of the signal currents as distinct from the actual values of the current. In 15 direct current signaling arrangements it is the rise and fall of the actual value of the currents which controls the impulse responding equipment. The rise and fall of the envelope of alternating currents can be readily determined by rectification as is well-known.

According to one feature of the invention an impulsing circuit in which the impulses consist of breaks in a direct current circuit is characterised by the provision of impulse responsive means, including a timing device, which are adapted to respond to either the fall or rise of the current during impulsing so that when the interval after a decrease or rise of the current in the direct current circuit without a further decrease or rise taking place exceeds a predetermined time a control operation is effected. Preferably a transformer is employed which causes unidirectional impulses to be derived on the fall and rise of the current, unidirectional impulses of one direction only being arranged to start the timing device and restart it with each succeeding impulse.

According to a further feature of the invention direct-current impulse-responsive equipment is provided including a gas discharge tube in which the change at the beginning of each impulse as received is arranged to initiate a control operation which is subsequently completed independently of the remainder of the impulse.

According to a further feature of the invention impulse responsive equipment is provided in which the change at the end of each impulse as received

is arranged to initiate a control operation which is subsequently completed independently of the beginning of a succeeding impulse.

According to a further feature of the invention which is particularly useful in connection with supervision over lines of poor transmission characteristics two gas discharge tubes are provided, one responsive to a change of signaling current to prepare the second tube for operation, which second tube can only operate when the signaling current changes in the opposite direction.

According to a further feature of the invention unidirectional impulses in opposite directions are derived due to the rise and fall in the value of the signaling currents respectively which impulses are applied to the grid of a gas discharge tube arranged so that impulses in one selected direction only can affect a signal-responsive device in the anode circuit.

At the present time telephone exchanges are usually provided with equipment which will only respond to impulses having a make to break ratio within predetermined limits which can hardly be obtained over lines having poor transmission characteristics and another of the objects of the invention is to enable impulses to be transmitted over a line having poor characteristics and arranging that such impulses should operate the selectors reliably.

According therefore to another feature of the invention trains of impulses are transmitted over a line or cable for the purpose of controlling impulse responding equipment in response to changes in one sense only of currents flowing over said lines, translating equipment being provided to cause impulses to be transmitted numerically equal to those received, but modified so as to be of a character suitable for the operation of the impulse responding equipment. This can conveniently be effected by an impulse regenerator of the electro-mechanical type.

A further object of the invention concerns the prevention of false operation by parasitic currents. Where a line is subject to parasitic currents it is obvious that if the parasitic currents are of the same nature or more powerful than the signals to be transmitted over the line, the line will not be capable of being used reliably. However parasitic currents are usually of a different nature and therefore it is possible to make good use of a line even although the parasitic currents may be quite considerable.

According therefore to a further feature of the invention the change in the value of the signaling currents is adapted to cause the generation of a uni-directional impulse, the signal-responsive means being adapted to respond only to such a unidirectional impulse if in a certain direction and having a strength combined with duration which ensures that the impulses are not due to parasitic currents of a weaker character or of shorter duration than the signaling impulses. One way in which this may be effected is by employing a biasing battery for a grid-controlled gas discharge tube and by employing for a transformer an ordinary telephone relay which is not responsive efficiently to the high frequency currents or to impulses of very short duration or preferably in addition or alternatively to the inefficient transformer a condenser-charging arrangement may be provided whereby the bias on the grid of a gas discharge can only be overcome either by impulses of high voltage if the duration is short, or by lower voltage impulses if the im-

pulses persist sufficiently long to charge the condenser to the desired voltage.

The invention will be better understood from the following description of a portion of a telephone system showing the invention applied both to impulsing and supervisory circuits, reference being had to the accompanying drawings, comprising Figs. 1-3. Of these, Fig. 1 shows the circuits of an outgoing direct current loop dialling relay set at a sleeve-controlled operator's position suitable for use in the provision of "on demand" trunk telephone service and assumed to be located at an exchange X. Fig. 2 shows the circuits of an incoming direct current dialling relay set at an automatic exchange Y which relay set is assumed to terminate a long junction line extending between the two exchanges X and Y. Fig. 3 shows an improved circuit for preventing false signaling by parasitic currents.

Dialled impulse transmission between the outgoing exchange X and the incoming exchange Y is effected on the usual 2-wire metallic loop direct current basis, while supervision of the actions of the called party at exchange Y is relayed back to the outgoing relay set at exchange X in the usual manner by reversing the connections to line of the incoming battery feeding bridge at exchange Y. It is assumed however that the length of junction line between the two exchanges X and Y greatly exceeds the hitherto accepted maximum limit for direct current junction working and this form of working is rendered possible by the improved arrangement according to the invention.

It will be seen that the supervisory signal and impulse signal receiving arrangements at the respective exchanges X and Y incorporate hot-cathode three-electrode gas discharge tubes which are transformer-coupled to line in such manner that they are triggered into operation by a voltage surge characteristic of the incremental or decremental wave form of the particular signal they are to receive. They thereupon effect the operation of the relevant responding relay in a local circuit which is independent of the length of the signaling line and moreover by virtue of the lock-in characteristic of the gas discharge tubes, the relays can be maintained operated independently of the received signal until the required operation has been effected.

In order to permit the use of only a single gas discharge tube per impulse responding device, the incoming relay set in the arrangement illustrated is provided with what may be termed a speed-timing impulsing circuit which operates in association with an electro-mechanical impulse storage and regenerative device. The regenerator, which is assumed to be of the type disclosed in specification No. 2,188,461, McClew and Woodland, is adapted to receive signals from the gas discharge tube anode relay characteristic of the impulse trains received over the junction line, and in response thereto is adapted to re-transmit, to automatic selector switches of normal step-by-step type, loop impulses correct as regards make and break ratio and speed. The speed timing circuit is of the type disclosed in our previously mentioned application No. 434,762 and it does away with the separate time measuring functions of the slow-to-release B and C relays usually provided in association with an impulse receiving relay A. It comprises a single time measuring circuit including a condenser, a resistance and a neon tube and is adapted to com-

pare the total length of the make plus break period of each impulse of a received train with a predetermined period substantially equal to the total length of each impulse at the slowest impulsing speed tolerated in practice. This circuit is set into operation at the beginning of the first impulse of a train and is restored to normal by each successive impulse of a train until the last pulse is received, after which it functions either to initiate release of the connection or to mark mechanically on the regenerator the value of the particular digit which has been received, according to the conditions obtaining at the time.

These arrangements will be better appreciated from the following description of the circuit operations which occur when an operator at exchange X sets up a connection to a subscriber connected to the automatic exchange Y.

To do this she will insert the calling plug of the cord circuit in use into jack J whereupon, assuming that the appropriate cord circuit speaking key has been thrown, battery will be extended from the position circuit over the sleeves of the plug and jack to operate relay SR by way of its lower winding. This relay on operating at contacts *srl* brings up relay SS which at contacts *ss1* extends a resistance battery potential back over lead K and the IDF strapping connection to operate the supervisory lamp relay SLR and hence to light a busy lamp associated with the outgoing relay set taken into use. Relay SS also at contacts *ss5* extends a loop over common leads 11 and 12 to start up the flicker earth generation equipment and at *ss2* connects flicker earth over common lead 10 back to the operator's cord circuit via the low resistance lower winding of relay SR so as to flash a lamp at the operator's position to indicate that the relay set is ready to receive dialled impulses. At *ss4* relay SS completes a circuit for the series-connected filaments of three-electrode gas discharge tubes GDT¹ and GDT² in readiness for their subsequent use when supervisory signals are transmitted back from the distant incoming relay set.

The operator now throws her position dial key whereupon the tip and ring conductors T and R are looped by an impedance having a centre tapping connected to battery through a resistance and accordingly relay RR is operated over the ring conductor. This relay at contacts *rr1* brings up relay DT which at contacts *dt1* locks independently of relay RR, at *dt2* disconnects the flicker earth from the pack sleeve and replaces it by the earthed winding of relay MR which however is unable to operate at this stage owing to the fact that the operation of the dial key in the position circuit has introduced a high resistance into the sleeve circuit; relay SR however remains operated under these conditions. Relay DT also at contacts *dt3* and *dt4* disconnects the operating circuit for relay RR and provides a through connection from the jack tip and ring conductors to the outgoing side of the circuit, whereupon the loop in the position circuit is extended forward to operate the sensitive line-current feeding relay A in the incoming relay set at exchange Y. This relay on operating brings up relay B which completes a circuit for the filament of the tube GDT³, completes a locking circuit for itself, prepares a loop impulsing circuit at contacts *b3* to the incoming selector switch associated with the incoming relay set in question, and at *b4* applies a guarding and holding earth to the P conductor of this selector.

The first digit of the required number at ex-

change Y is now dialled and when the operator's dial is moved off normal, the impulse springs of the dial are looped across the tip and ring conductors and the original seizing impedance is

5 short-circuited; hence on the release of the dial, make and break impulses are delivered to relay A in the distant relay set in the usual manner. It will be noted that relay A cannot strictly be referred to as an impulsing relay since, in the 10 present circumstances, it acts primarily as a transformer which serves to convert the impulses of a received train into voltage surges which trigger the tube GDT³ and thereby operate the quick-acting relay P. Relay A does however exercise the function of a relay in enabling the tube filament circuit to be under the control of the calling party so as to avoid the necessity for continuous operation thereof. It does not necessarily release during impulsing although as 15 shown it will operate and release over the line circuit, that is to say the break period of an impulse may not be sufficient to enable it to release.

In response to the first break impulse delivered by the operator's dial, the line current falls and 20 as a result a voltage surge is induced in the middle winding of relay A in such a direction as to reduce the normal negative bias on the grid of tube GDT³ with respect to the filament. The tube is thereupon triggered into operation and 25 brings up the anode relay P. The characteristic of the tube is such that when once it ionises, the grid loses control and the tube is subsequently extinguishable only by opening the anode or filament circuits. Relay P on operating, at contacts *p1* completes an energising circuit for the 30 regenerator receiving magnet RM and relay C in parallel, and also at *p2* completes a rapid discharging circuit via resistance YP for the condenser QF of the so-called speed timing arrangement. Relay C at contacts *c2* completes a local locking circuit for itself, at *c3* energises the 35 regenerator marking magnet MM, the function of which will be described later, and at *c4* prepares a charging circuit for the speed timing condenser

40 QF via resistance YQ to positive battery, which circuit becomes effective on the release of relay P after the satisfactory operation of magnet RM. Owing to the inherent lock-in feature of the tube GDT³, relay P will remain operated until magnet RM has fully energised, no matter how short is the duration of the voltage surge produced by the break impulse, and when magnet RM has 45 fully operated, its interrupter contacts *rm* open to extinguish the tube and release relay P.

50 The regenerator may be described as comprising essentially a receiving arm and a sending arm which are arranged on opposite sides of a plate carrying a circular row of pins. The receiving arm is rotated step-by-step on the reverse drive principle in response to the impulses received by magnet RM and carries with it a marking lever which is released on the de-energisation of the marking magnet MM at the 55 end of each train of received impulses and which thereupon pushes a pin corresponding to the digit dialled through the pin plate into the path of the sending arm. For each digit received a corresponding pin is pushed through the plate and these pins serve to determine the movement of the sending arm which controls the generation of outgoing pulses by means of the regenerator impulsing springs IMP.

60 Returning again to the operation of the magnet RM, relay P on releasing de-energises this magnet, whereupon the receiving arm is advanced

one step and thereupon brings about the operation of the regenerator off-normal springs N and a circuit is accordingly prepared for relay BY over contacts N1 in readiness for subsequent pulsing out from the regenerator to the group selector.

At the end of the first break period, the dial springs on reclosing cause the line current to rise to its normal value and in response thereto a further voltage surge is induced in the middle winding of relay A. In this instance however since the current is rising, the induced voltage will be such as to bias the grid of the tube GDT3 more negatively and so it will not strike at this time. Relay P therefore remains inoperative until the commencement of the second break impulse when the tube GDT3 again strikes and re-operates relay P to advance the receiving disc a further step.

Considering the speed timing arrangements, the values of the condenser QF and resistance YQ are such that if the charging circuit is undisturbed for a period of the order of 120 milli-seconds, condenser QF will be charged to the striking voltage of the neon tube NT and this tube will flash and energise relay H which initiates the sending out of the digit stored in the regenerator in a manner to be described. This period of 120 milli-seconds added to the RM magnet operating time and the P relay release time, gives a total period of the order of 143 milli-seconds which is representative of a complete impulse from a dial of standard ratio which is running at the slowest allowable speed of seven impulses per second.

Assuming that the digit dialled is 2 or more, the second negative bias surge will occur before condenser QF is able to charge up to the striking voltage of neon tube NT and hence when relay P re-operates on this surge, a rapid discharge circuit will again be completed for condenser QF via contacts p2 and resistance YP so as to restore this condenser to normal. Magnet RM is energised a second time and condenser QF commences to charge again when the operation of this magnet releases relay P and the cycle of operations described is repeated until the last impulse of the train is received.

Approximately 140 milli-seconds after the commencement of the break period of the last impulse of the train, the voltage on condenser QF rises to the striking value of neon tube NT, whereupon the tube flashes and brings up relay H. This relay thereupon at contacts h1 releases relay C and at h2 renders the operation of relay B dependent on the continued operation of relay A from the calling operator's position. Relay C on releasing, at contacts c1 completes an operating circuit for relay BY which locks and at c3 opens the circuit for the marking magnet MM, while at c4 it disconnects any further charging circuit for condenser QF. The marking magnet MM in restoring causes the lever carried by the receiver arm to push a pin corresponding to the digit dialled into the path of the sending arm. Relay BY at contacts by1 and by2 connects the regenerator impulsive springs IMP across the negative and positive conductors outgoing to the selector switch, whereupon the impulsive relay therein is operated and prepares the switch for receiving the train of impulses corresponding to the stored digit. A circuit is also completed at contacts by4 for relay IP which is slow to operate and release and at by5 for relay IS which is quick to operate and slow to release.

Relay IS operates first but without effect and when relay IP operates, it opens the circuit of relay IS at contacts ip1 so that when the latter releases, an energising circuit is completed for the regenerator transmitting magnet TM.

It will be understood that by the operation of magnet TM the pin in the regenerator which was displaced to mark the termination of the last train of impulses involved in the previous 10 call is pushed out of the path of the sending arm and back to its normal position by a resetting pin designated RP connected in circuit with relay IP, but, owing to the stepped head on the reset pin as indicated diagrammatically 15 in the drawings, the sending arm is not immediately released but remains held until magnet TM is de-energised. Magnet TM at its contacts tm disconnects relay IP which on releasing after its slow period opens the magnet energising circuit and as fully described specification No. 2,188,461 previously mentioned, the sending arm is released and rotates until the reset pin comes up against the stop pin which has been set to indicate the termination of the first train of 20 pulses received thereon. During this rotation of the sending arm the springs IMP are intermittently operated to generate standard impulses at the rate of one for each pin passed over by the sending arm.

30 It will be noticed that since the reset pin RP is not connecting with any stop pin such as SP during the movement of the sending arm, relay IP cannot be re-operated, and the impulses generated by the impulsive springs IMP are delivered to the group selector over the outgoing negative and positive conductors. Relay IS is re-operated during this time and serves subsequently for the purpose of timing the interdigital pause.

40 Previous to, and during this time, further trains of dialled impulses may be received and effect setting of the receiving arm and it will be appreciated that the two operations of reception and transmission may go on simultaneously but 45 independently of each other.

When the sending arm comes up against the stop pin indicating the termination of the first received digit, relay IP is again operated and relay IS is disconnected. After the release time 50 of relay IS which determines the interdigital pause, and assuming that at least one further digit has by this time been stored on the regenerator, the sending magnet TM again receives a momentary energisation in order to release the sending arm once more to generate a second train of impulses in the manner described.

When all the digits received have been retransmitted, the sending arm will catch up with the receiving arm whereupon the off-normal contacts NL open and release relay BY. Relay BY thereupon at contacts by1 and by2 re-completes the through connection by way of condensers QD and QF from the incoming to the outgoing sides of the relay set. Relay IS will have been held operated during the sending out of the last digit of the transmitted train in the usual manner and during its slow-to-release period it maintains a holding path via contacts 60 is2, impulse springs IMP and resistance YK across the outgoing leads to minimise the effect on the distant final selector impulse receiving relay of the introduction of the supervisory relay 2D, polarised by virtue of the dry plate rectifiers MRA and MRB, and retard 2I across the out-

going lines in place of the initial short-circuit path via the springs IMP.

The operator on concluding the dialling of the required number will restore her position dial key to the normal position, whereupon the resistance introduced into the sleeve circuit by the operation of this key will be short-circuited and the resultant increased current flow over this circuit will enable relay MR in the outgoing relay set to operate. This relay opens the holding circuit for relay DT at contacts *mr1* and at *mr2* completes a local locking circuit for itself, and relay DT on releasing at contacts *dt3* and *dt4* re-inserts the transmission condensers QA and QB in the speech transmission line and extends a full earth back via contacts *d3*, *mr3*, *dt2* and *ss2*, the low resistance winding of relay SR and the sleeve circuit to light the cord circuit calling supervisory lamp to indicate to the operator that a reply is being awaited from the distant called subscriber. Relay MR also at *mr6* connects the tubes GDT₁ and GDT₂ across the line by way of the transformer TR and at *mr5* connects the supervisory relay D to the anode circuit of tube GDT₂.

If the called subscriber is busy, the operator will receive busy tone from the distant final selector and will act accordingly. If he is free, however, and answers the call, when he replies relay 2D in the incoming relay set is operated in the usual manner by battery reversal from the final selector, whereupon the battery feed over the incoming junction is reversed at contacts *2d1* and *2d2*. As a result a voltage surge is induced in the secondary winding of the transformer TR at the outgoing relay set and this will be of such polarity that the normal negative bias on the grid of tube GDT₂ will be reduced and this tube thereupon triggers into operation and brings up relay D. The tube continues to conduct after the termination of the surge until such time as the anode or cathode circuit is broken and relay D is therefore maintained operated during this time. This relay on operating, at contacts *d1* connects relay RR to the anode circuit of the other tube in readiness for a subsequent supervisory signal, and at *d2* extends a battery line feed to the jack side of the circuit via the windings of retard I, while at *d3* the full earth connection is removed from the sleeve circuit so as to extinguish the lamp on the calling side of the operator's cord circuit to indicate that the called party has answered.

The operator now releases her cord circuit speaking key to dissociate this circuit from her position and to cause a through connection to be provided therein between the two sides of the circuit. The calling and called parties are now connected to one another and conversation may take place.

At the end of the conversation, when the subscribers replace their receivers, the hanging up of the calling subscriber will be communicated to the operator's cord circuit in the usual manner, while when the called subscriber hangs up, the battery feed to line at exchange Y is restored to normal by the restoration of relay 2D. The resultant voltage surge produced in transformer TR by battery reversal over the line causes tube GDT₁ to trigger and bring up relay RR which at *rr2* releases relay D. Relay D thereupon by replacing the earth on the sleeve circuit at *d3* re-lights the operator's cord circuit calling supervisory lamp and the operator on

seeing both the answering and calling lamps glowing on the cord circuit concerned will withdraw the plugs.

The withdrawal of the calling plug from the jack J releases relay SR which in turn releases relays SS and MR, whereupon the loop extended forward to exchange Y via transformer TR is opened and the filament circuits of tubes GDT₁ and GDT₂ are opened to release the locked-in relay RR. The opening of the loop to exchange Y releases relay A in the distant incoming relay set and the release of this relay renders the continued holding of relay B dependent on the continued normal condition of relay H. The fall in the current flow in the windings of relay A however, simulates the commencement of a break impulse and tube GDT₃ therefore comes into operation and brings up relay P. Relay P on operating functions as for a single break impulse and the speed timing circuit is brought into operation. After the lapse of 140 milli-seconds, relay H is operated to release relay B and also relay C which will have been operated on the operation of relay P and the regenerator will send out the equivalent of a stored digit 1 into an open circuit after which the incoming relay set will be ready for further use. Relay B on releasing opens the loop forward to the incoming selector switch and so brings about release of the automatic equipment taken into use.

Substantial immunity from false operation by transient signals of a parasitic nature will be effected by virtue of the standing negative bias on the gas discharge tube control grid, which bias will be made such that the maximum expected value of parasitic surge voltage will not be sufficient to cause the tube to strike, as well as by the inefficiency of the relay as a transformer at high frequencies. This voltage discrimination arrangement presupposes that the voltage kick resulting from the beginning or end of a signal wave, according to which is being utilised, shall always be sufficient to reduce the standing negative potential to a value such that the tube will strike, that is to say, that the kick shall be greater than a transient surge voltage.

In many cases the line conditions will be such that the front and termination of a received signal wave will not be steep, so that the induced kick in the transformer secondary winding will not be great. Whereas an ideal rectangular wave-form pulse may give a momentary induced kick of say 10 volts, the actual wave-form due to distortion may give a kick in the secondary winding of the order of say 2 volts which while being much less in value will persist during the comparatively slow rise or fall in the signaling current, that is to say for example for a period of 10 milli-seconds instead of one milli-second or less with the rectangular wave-form. The voltage due to a transient parasitic signal of rectangular wave-form must be less than the voltage represented by a signal also of rectangular wave-form, but it may be greater than the voltage derived from an actual distorted wave as it is likely to be either of a momentary nature or fluctuating or alternating in value. False operation under these conditions can be avoided by employing the time-voltage discrimination arrangement for instance as shown in Fig. 3.

Referring to this figure, it will be seen that a condenser QG is introduced into the grid biasing circuit in such manner that any change in the grid voltage is dependent on the build-up of a charge on the condenser. It will be under-

stood that the standing negative voltage on the grid of tube GDT3 and the values of resistance YJ and condenser QG are such that the striking voltage will not be built up on condenser QG unless the induced voltage is sufficiently large to build up the voltage in the condenser before it falls away. This can be effected by a momentary pulse if the voltage is sufficiently great or by a prolonged pulse of less voltage provided that the voltage is greater than the voltage required to strike the tube and persists long enough to enable the voltage across the condenser to reach the striking voltage. Surges generally if momentary will give a voltage less than that required to strike the tube and if they persist will either fluctuate or alternate in value so that the voltage across the condenser cannot build up to the striking voltage.

The voltage from a distorted signal, which may have a maximum value less than the surge voltage, will however be able to cause the tube to strike, since its persistence for up to say 10 milli-seconds will allow the condenser QG to charge up to the requisite striking value. In the ideal case where a rectangular pulse is received, then although the kick will be momentary its value will be greater and it will persist longer than the usual surge voltages.

The arrangements proposed according to the invention will it is believed be found to give more reliable impulsing over lines in poor condition than is possible with the usual impulsing methods and allowing for the greater sensitivity will be as immune if not more immune to outside disturbances.

Alternatively to the arrangements described above two gas discharge tubes might be used, one responding to decremental wave fronts and the other to incremental wave fronts, and since both parts of an impulse will now be detected as against one part only with the speed timing arrangements described, the more well-known types of impulse receiving circuits such as those using B and C relays can be employed. As a further alternative it is possible that use might be made of a single gas discharge tube which would respond to either an incremental or decremental wave front, and which might be combined with any of the well-known impulse correction devices. In this case the lock-in nature of the gas discharge tube would play an important part in the impulse correcting device along the lines already outlined in the foregoing description.

It is not essential that a regenerator be provided at the incoming relay set, as shown, if the automatic selector train is equipped with speed timing impulsing arrangements, since the signals could in this instance be delivered direct from the relay P to the various selectors involved. It may also be desirable for the triggering of the gas discharge tube in the incoming relay set to take place on the incremental surge at the termination of each impulse break period instead of on the decremental surge as described.

The grid-controlled gas discharge tubes as proposed to be used in this invention may be of such types as the mercury vapour, argon and neon tubes. The preferable type as so far tested is the mercury vapour.

What we claim as new and desire to secure by Letters Patent is:

1. In a signaling system, a transformer having two windings, a source of current connected to one of said windings to cause current to flow over said winding in a certain direction, means for at

times reversing the direction of said flow of current and at other times restoring said flow of current to said certain direction, said reversal effective to induce a transitory potential of one polarity in the other winding of said transformer and said restoration effective to induce a transitory potential of the opposite polarity in said other winding, a pair of grid-controlled gas discharge tubes, at least one of said tubes having its grid connected to said other winding whereby said one tube is effective to strike responsive to a transitory potential of one of said two polarities being induced in said other winding, means operated responsive to said one tube striking for conditioning the other of said tubes to strike responsive to a transitory potential of the other of said two polarities being induced in said other winding, and a plate circuit for said other tube thereafter energized responsive to a transitory potential of said other polarity being induced in said other winding.

2. In a signaling system, a transformer having two windings, a source of current connected to one of said windings to cause current to flow over said winding in a certain direction, means for at times reversing the direction of said flow of current and at other times restoring said flow of current to said certain direction, said reversal effective to induce a transitory potential of one polarity in the other winding of said transformer and said restoration effective to induce a transitory potential of the opposite polarity in said other winding, a pair of grid-controlled gas discharge tubes, at least one of said tubes having its grid connected to said other winding whereby said one tube is effective to strike responsive to a transitory potential of one of said two polarities being induced in said other winding, means operated responsive to said one tube striking for conditioning the other of said tubes to strike responsive to a transitory potential of the other of said two polarities being induced in said other winding, a plate circuit for said other tube thereafter energized responsive to a transitory potential of said other polarity being induced in said other winding, and means controlled by the energization of said plate circuit for extinguishing said one tube.

3. In a signaling system, a transformer having two windings, a source of current connected to one of said windings to cause current to flow over said winding in a certain direction, means for at times reversing the direction of said flow of current and at other times restoring said flow of current to said certain direction, said reversal effective to induce a transitory potential of one polarity in the other winding of said transformer and said restoration effective to induce a transitory potential of the opposite polarity in said other winding, a pair of grid-controlled gas discharge tubes, at least one of said tubes having its grid connected to said other winding whereby said one tube is effective to discharge responsive to a transitory potential of one of said two polarities being induced in said other winding, means controlled by said discharge for conditioning the other of said tubes to discharge responsive to a transitory potential of the other of said two polarities being induced in said other winding, a discharge circuit for said other tube thereafter energized responsive to a transitory potential of said other polarity being induced in said other winding, and means controlled by the

energization of said discharge circuit for terminating the discharge of both said tubes.

4. In a signaling system, a transformer having two windings, a source of current connected to one of said windings to cause current to flow over said winding in a certain direction, means for at times reversing the direction of said flow of current and at other times restoring said flow of current to said certain direction, said reversal effective to induce a transitory potential of one polarity in the other winding of said transformer and said restoration effective to induce a transitory potential of the opposite polarity in said other winding, a pair of grid-controlled gas discharge tubes each having its grid connected to said other winding, one of said tubes having a normally disabled discharge circuit, the other of said tubes effective to discharge responsive to a transitory potential of one of said two polarities being induced in said other winding, means controlled by the discharge of said other tube for enabling said discharge circuit of said one tube, whereby, responsive to a transitory potential of the other of said two polarities being induced in said other winding, said one tube discharges and hence causes said discharge circuit to be energized, means controlled by said energization of said discharge circuit for terminating the discharge of said other tube, said second means effective responsive to the termination of the discharge of said other tube to disable said discharge circuit of said one tube, thereby to terminate the discharge of said one tube.

5. In a signaling system, a circuit upon which impulses of different polarity are impressed alternately, a pair of gas discharge tubes each having a grid, means for connecting said grids to said circuit so that one of said tubes is brought to its critical grid potential whenever an impulse of one of said polarities is impressed upon said circuit and the other of said tubes is brought to its critical grid potential whenever an impulse of the other of said polarities is impressed upon said circuit, each of said tubes effective to fire when brought to its critical grid potential, means controlled by said one tube, upon firing, for extinguishing said other tube, and means controlled by said other tube, upon being extinguished, for extinguishing said one tube.

6. In a signaling system, a circuit upon which impulses of different polarity are impressed alternately, a pair of gas discharge tubes each having a grid, means for connecting said grids to said circuit so that one of said tubes is brought to its critical grid potential whenever an impulse of one of said polarities is impressed upon said circuit and the other of said tubes is brought to its critical grid potential whenever an impulse of the other of said polarities is impressed upon said circuit, each of said tubes effective to fire when brought to its critical grid potential, and means controlled by each of said tubes for extinguishing the other tube.

7. In a signaling system, a circuit over which current is flowing in a particular direction, means operated at will first to reverse the direction of said current flow and then, after a variable interval of time, to restore said current flow to its original direction, a pair of gas discharge tubes, means coupling one of said tubes to said circuit so that it will strike responsive only to the transient current condition existing in said circuit during the time that said current flow is being changed from said particular direction to the reverse direction, and means controlled by said

one tube, upon striking, for conditioning the other of said tubes for operation, whereby said other tube will strike responsive only to the transient current condition subsequently existing in said circuit during the time that said current flow is being restored to said particular direction from said reverse direction.

8. In a signaling system, a circuit over which current is flowing in a particular direction, means operated at will first to reverse the direction of said current flow and then, after a variable interval of time, to restore said current flow to its original direction, a gas discharge tube having a grid, and means for coupling said grid to said circuit so that said tube will strike responsive only to the transient current condition existing in said circuit during the time that said current flow is being changed from said particular direction to the reverse direction.

9. In a signaling system, a circuit over which current is flowing in a particular direction, means operated at will first to reverse the direction of said current flow and then, after a variable interval of time, to restore said current flow to its original direction, a gas discharge tube having a grid, and means for coupling said grid to said circuit so that said tube will strike responsive only to the transient current condition existing in said circuit during the time that said current flow is being restored to said particular direction from the reverse direction.

10. In a telephone system wherein the direction of the flow of current over the speech circuit is reversed at times, a pair of gas discharge tubes, means normally disabling one of said tubes, means whereby the other of said tubes is effective to discharge responsive only to a reversal of said current flow from one particular direction to the opposite direction, said first means controlled by the discharge of said other tube for enabling said one tube, said one tube thereafter effective to discharge responsive only to a subsequent reversal of said current flow from said opposite direction to said one direction.

11. In a telephone system wherein the direction of the flow of current over the speech circuit is reversed at times, a pair of gas discharge tubes, means whereby one of said tubes is effective to fire responsive only to a reversal of said current flow from one particular direction to the opposite direction, and means whereby the other of said tubes is effective to fire responsive only to a reversal of said current flow from said opposite direction to said one direction.

12. In a signaling system wherein signaling is effected by reversals in the direction of the flow of current over a signaling circuit, a transformer having one winding in said circuit, a grid-controlled gas discharge tube having its grid connected to another winding of said transformer, said tube effective to fire responsive to certain of said reversals but not responsive to others depending upon the polarity of the potential induced in said other winding by such reversals, and a plate circuit for said tube energized whenever said tube fires.

13. In a signaling system, a transformer having two windings, means for impressing a square wave upon one of said windings, a grid-controlled gas discharge tube having its grid connected to the other of said windings whereby said tube is effective to strike whenever the voltage induced in said other winding by said square wave is of a certain polarity, a second gas discharge tube, and means controlled by said first tube, whenever it strikes,

for conditioning said second tube for operation, whereby said second tube is effective to strike whenever the voltage induced in said other winding by said square wave is of the opposite polarity.

14. In a signaling system, a transformer having a primary winding and a secondary winding, means for impressing impulses upon said primary winding, the beginning of each impulse effective to induce a transitory potential of a certain polarity in said secondary winding, and the end of each impulse effective to induce a transitory potential of a different polarity in said secondary winding, a gas discharge tube having an anode circuit and a grid for controlling said circuit, a connection from said grid to said secondary winding whereby said tube is effective to strike responsive to a transitory potential of one of said two polarities being induced in said secondary winding but is not effective to strike responsive to a transitory potential of the other of said polarities being induced in said secondary winding, and means in said anode circuit operated responsive to said tube striking.

15. In a signaling system, a transformer having two windings, means for impressing electrical impulses upon one of said windings, the beginning of each impulse effective to induce a transitory potential of a certain polarity in the other of said windings and the end of each impulse effective to induce a transitory potential of a different polarity in the other of said windings, a grid-controlled gas discharge tube having its grid connected to said other winding whereby said tube is effective to discharge responsive to said induced potential whenever said induced potential is of one of said two polarities, said tube being non-responsive to an induced potential of the other of said two polarities, and means controlled by each discharge of said tube for terminating that discharge.

16. In a signaling system, a transformer having two windings, means for impressing electrical impulses upon one of said windings, a condenser connected to the other of said windings and charged by the potential induced in said other winding responsive to each said impulse, a grid-controlled gas discharge tube having its grid connected to said condenser whereby said tube is effective to discharge whenever the charge on said condenser reaches a certain value, and means controlled by each discharge of said tube for terminating that discharge.

17. In a signaling system, a transformer having two windings, means for impressing electrical impulses upon one of said windings, a grid-controlled gas discharge tube having its grid connected to the other of said windings whereby said tube is effective to discharge once responsive to each impulse impressed upon said winding, and means effective to terminate each said discharge substantially immediately regardless of the length of the impulse to which that discharge is responsive.

18. In a signaling system, a transformer having two windings, means for impressing electrical impulses upon one of said windings, a grid-controlled gas discharge tube having its grid connected to the other of said windings whereby said tube is effective to discharge once responsive to each impulse impressed upon said winding, and means for terminating the discharge occasioned by each impulse before the beginning of the next impulse.

19. In a signaling system, a transformer having two windings, means for impressing electrical im-

pulses upon one of said windings, a grid-controlled gas discharge tube having its grid connected to the other of said windings whereby said tube is effective to discharge once responsive to each impulse impressed upon one said winding, means effective to terminate each said discharge substantially immediately regardless of the length of the impulse to which that discharge is responsive, a device, time delay means conditioned by each discharge of said tube to operate said device after a predetermined interval of time, and means responsive only to another discharge of said tube within said interval of time for preventing the operation of said device by said time delay means.

20. In a signaling system, a circuit over which trains of impulses are transmitted at times, a gas discharge tube, means for associating said tube with said circuit whereby said tube is effective to fire at a particular point in each impulse, said point being the same for all said impulses, timing equipment, means operated under control of said tube whenever said tube fires for causing said equipment to start a timing operation, and a device operated under control of said timing equipment only if said tube fails to fire again within a predetermined interval of time after the beginning of any such timing operation.

21. In a signaling system, a transformer having two windings, means for impressing a train of impulses upon one of said windings thereby periodically to induce a certain potential in the other of said windings, a gas discharge tube associated with said other winding and effective to discharge whenever said certain potential is induced in said other winding, a device, time delay means conditioned by each such discharge of said tube to operate said device after a predetermined interval of time, and means responsive only to another discharge of said tube within said interval of time for preventing the operation of said device by said time delay means.

22. In combination, a pair of gas discharge tubes, means operated to discharge one of said tubes at intervals, time delay means conditioned by each such discharge of said one tube to discharge the other of said tubes after a predetermined interval of time, and means responsive only to another discharge of said one tube within said interval of time for preventing the discharge of said other tube by said time delay means at the end of such interval.

23. In a signaling system, a gas discharge tube having a grid, means for impressing upon said grid at different times transitory electrical impulses of different polarity, said tube effective to discharge responsive only to impulses of a particular polarity impressed upon its grid, timing equipment, means operated responsive to each discharge of said tube for causing said equipment to start a timing operation, and a device operated under control of said timing equipment only if said tube fails to discharge again within a predetermined interval of time after any discharge.

24. In a signaling system wherein electrical impulses of different polarity are transmitted alternately, a gas discharge tube having a grid, means for impressing said impulses upon said grid, said tube effective to discharge responsive only to alternate ones of said impulses, a device, time delay means conditioned by each discharge of said tube to operate said device after a predetermined interval of time, and means responsive only to another discharge of said tube within

said interval of time for preventing the operation of said device by said time delay means.

25. In a signaling system, a circuit upon which electrical impulses of different polarity are impressed alternately, means responsive to the impulses of one polarity impressed upon said circuit but non-responsive to the impulses of the other polarity, a device, time delay means conditioned by each response of said first means to an impulse of said one polarity to operate said device after a predetermined interval of time, and means effective only upon the response of said first means to another impulse of said one polarity within said interval of time for preventing the operation of said device by said time delay means. 15

26. In a signaling system, a transformer having two windings, means for impressing a square wave upon one of said windings, a grid-controlled gas discharge tube having its grid connected to the other of said windings whereby a discharge of said tube is initiated whenever the voltage induced in said other winding by said square wave is of a certain polarity, and means controlled by each discharge for terminating that discharge a predetermined interval after its initiation.
